DESIGN FOR A HANDLE

Herman E. De Vries, New York, N. Y., assignor to
H. T. Cushman Mfg. Co., North Bennington, Vt.

Application October 16, 1934, Serial No. 53,630

Term of patent 7 years

To all whom it may concern:

Be it known that I, Herman E. De Vries, a citizen of the United States, residing at New York city, in the county and State of New York, have invented a new, original, and ornamental Design for a Handle, of which the following is a specification, reference being had to the accompanying drawing, forming part thereof.

I claim:

The ornamental design for a handle substantially as shown.

HERMAN E. DE VRIES.
